Primary Examiner — Sandra Snapp(74) *Attorney, Agent, or Firm* — Revolution IP, PLLC(57) **CLAIM**

The ornamental design for a “table with built in cooler,” as shown and described.

DESCRIPTION

FIG. 1 is a perspective view of table with built in cooler showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a partially exploded view thereof, which illustrates a chair separated from the table and bottles put in the cooler; and,

FIG. 9 is another perspective view thereof, which shows a bottom of the cooler of the table.

The broken line showing the bottles in FIG. 8 is for the purpose of illustrating environmental structure and forms no part of the claimed design.
